COED LOCK FOR VENETIAN BLINDS

Walter J. Stuber, Philadelphia, Pa., assignor to
Carey-McFall Company, Philadelphia, Pa., a
corporation of Pennsylvania

Original application March 6, 1940, Serial No.
322,604. Divided and this application June 25,
1940, Serial No. 342,345

3 Claims. (Cl. 156—17)

This invention relates to Venetian blinds and particularly to the lock for the elevating cords of the blind disclosed in the copending application, Serial No. 322,604 of which the present application is a division.

The object of the present invention is to provide a simple and highly efficient cord lock composed of a few simple parts which will cooperate to produce quick locking and easy releasing of the elevating cords and which will insure against accidental slipping of the cords with consequent dropping of the slats of the blind from their intended elevation.

The construction and operation of the cord lock of the present invention will be fully disclosed hereinafter, reference being had to the accompanying drawings, of which:

Fig. 1 is a front elevation of the blind with the cord lock mechanism holding the slats at a predetermined elevation;

Fig. 2 is a transverse section taken on the line 2—2, Fig. 1;

Fig. 3 is a sectional plan view taken on the line 3—3, Fig. 1; and

Fig. 4 is a sectional elevation taken on the line 4—4, Fig. 2.

As shown in Fig. 1, the blind 1 includes the usual bottom rail 2, slats 3, ladder tapes 4, 4 and elevating cords 5, 5.

The ladder tapes 4, 4 are secured at their upper ends to rockers 6, 6 respectively, which are secured to a tilt shaft 7 adapted to be rocked about the axes of aligned end pivots 8 and 9 carried by brackets 10 and 11 respectively.

Suitable mechanism 12, operable by a tilting chain 13 is provided for rocking the shaft 7 and thereby setting the slats 3, 3 at any desired angle, transversely, to the horizontal.

The pivot brackets 10 and 11 are carried by the head rail 15, which in turn, is supported on end brackets 16 and 17. The elevating cords 5, 5 pass upward from the bottom rail 2, through slots in the slats 3, 3, between the front and back tapes of each of the ladders 4, 4 to rollers or pulleys 18, 18 which are rotatably mounted in guide members 19, 19 provided for the ladder tapes 4, 4 at the rockers 6, 6 respectively.

From the guide rollers 18, 18 the elevating cords 5, 5 pass to and under a roller 100 which is rotatably mounted in a housing 82 carried by the bracket 11.

From the roller 100 the elevating cords pass upwardly then over and around the periphery of a roller 101 which is rotatably mounted on a shaft 102 having its ends secured in extensions

or legs 103 of a U shaped bracket 104 carried by the bracket 11. From the roller 101 the cords 5, 5 extend downwardly through an opening 105 formed in the bottom plate of the head rail 15 to be joined together at their lower ends in a common tassel or handle 106, whereby raising and lowering of said tassel will effect corresponding lowering and raising of the bottom rail 2 and the slats 3.

10 The slats may be maintained at any desired elevation by a locking catch 110, see Fig. 4, which is in the form of a U shaped lever having arms 111, 111 pivoted on a common pin 112 carried by the bracket 104 and connected at their outer ends by a cross plate 113. The cross plate 113 is provided with cross slits 114 and the metal adjacent said slits is bent inwardly, as indicated at 115, Fig. 4, to provide teeth adjacent the peripheral face of the roller 101 between which 15 and said teeth the elevating cords 5 extend. By swinging the cords 5 to the left, as viewed in Figs. 1 and 4 and pulling said cords downwardly said cords become released from the teeth 115 of the locking catch 110 permitting said catch 20 to drop until the lower edge thereof substantially contacts with and rests upon a cross plate 116 which joins the outer ends of arms 117, 117 and which constitute with the cross plate 116 an actuating lever 118 for the locking latch 110. 25 The arms 117, 117 are pivotally mounted on a common pivot 119 carried by the bracket 104.

With the latch 110 released in the manner above noted the cords 5 may be operated to raise or lower the blind, as desired. Then by swinging 30 said cords 5 to the right as viewed in Figs. 1 and 4, said cords, by reason of their passing through an opening 120 in the cross plate 116 of the actuator 118, swings said actuator to the right. In doing so the cords 5 engage the teeth 115 of 35 the locking latch 110 and while holding the cords in the position they have assumed while being swung to the right and leaving said cords move upwardly said cord will carry said teeth upwardly, 40 swinging the latch 110 about its pivot and pinching the cords between said teeth and the periphery of the roller 101.

45 Preferably the face of the roller 101 is circumferentially grooved at 101a for each cord 5, and these grooves are deposited in line with the holes 120, 120 in the lever 118 through which the cords 5, 5 extend, whereby the portions 5a, 5a of the cords, between the roller 101 and the lever 118, are maintained in substantially straight lines constituting a definite predetermined position of the cords with respect to the

teeth 115 of the locking lever 110, when the outer free end of the latter is resting on the cross bar 116 of the lever 118, so that by slight swinging of the lever 118 to the right, as viewed in Fig. 4, the fibres of the cords 5 will catch in the teeth 115 and raise the outer end of the lever 110 until the teeth pinch the cords against the face of the roller 101 as a result of the relationship existing between the pivot of the lever 110 and the axis of rotation of the roller 101. As the arcuate path described by the teeth 115 intersects the arcuate surface of the roller 101, with the cords 5, 5 disposed between the teeth and the roller, the cords will be pinched by the teeth 115 against the surface of the roller 101 and held against further upward movement. The weight of the blind supported by the cords 5, 5 accentuates this gripping and pinching action.

However, due to the relationship of the axes about which the roller 101 and lever 110 move, and the relation of the arc traversed by the teeth 115 with respect to the arc of the peripheral surface of the roller 101, and due to the fact that both cord pinching surfaces are movable and rock in the same direction about centers at one and the same side of the cords being pinched between the two, the locking grip on the cords is readily and easily broken by merely pulling downwardly on the free ends of the cords 5, 5 because there is no hard fast jamming of the cords against a fixed surface by a single rockable locking latch as is common in the prior art.

I claim:

1. A Venetian blind structure comprising cord actuated slat elevating means including a pulley for changing direction of movement of the operating cords from horizontal to vertical and vice versa, said pulley being rotatably mounted between two substantially parallel plate-like supports, a lock for said cords comprising a U-shaped lever pivoted to said supports at one side of the axis of rotation of said pulley and including a portion paralleling the face of said pulley and adapted to swing in a path to intersect with said pulley face to pinch said cords therebetween, said portion having spaced inwardly projecting edges for engaging said ropes when the latter are swung in one direction in tangential relation to said pulley face and to release

said ropes when the latter are swung in an opposite direction, and an actuator for said lever pivoted to said supports at the opposite side of the axis of rotation of said pulley with a transverse portion extending across said U-shaped lever adjacent the toothed portion thereof and provided with openings through which said ropes extend for swinging said actuator to operate said locking lever.

2. In a cord lock for Venetian blinds, a roller over which the cord passes and from which the cord hangs vertically, the axis of rotation of the roller being located at one side of the hanging portion of the cord, a locking lever rockable about an axis located below the axis of rotation of the roller at said one side of the hanging portion of the cord, teeth on said locking lever at the opposite side of the hanging portion of the cord and adapted to describe an arc intersecting the arc of that portion of the periphery of the roller about which the cord passes, and a lever rockable about an axis located above the axis of rotation of the roller and including a portion located below said locking lever, said lever portion having an opening through which the hanging portion of the cord extends in definite relation to the teeth of the locking lever.

3. In a cord lock for Venetian blinds, a roller over which the cord passes and from which the cord hangs vertically, the axis of rotation of the roller being located at one side of the hanging portion of the cord, a locking lever rockable about an axis located below the axis of rotation of the roller at said one side of the hanging portion of the cord, teeth on said locking lever at the opposite side of the hanging portion of the cord and adapted to describe an arc intersecting the arc of that portion of the periphery of the roller about which the cord passes, and a lever rockable about an axis located above the axis of rotation of the roller and including a portion located below said locking lever and affording a rest for the outer end of said locking lever when released from the cord, said lever portion having an opening through which the hanging portion of the cord extends in definite relation to the teeth of the locking lever.

WALTER J. STUBER.
